COMBINATION CAN PUNCH AND HANDLE
William J. Mitchell, 2010 Duthie Ave., Burnaby,
British Columbia, Canada

Filed Jan. 21, 1965, Ser. No. 426,727
4 Claims. (Cl. 30—16)

This invention relates to a combination punch and handle designed to open and hold cans which contain beverages, such as beer or the like.

In the pouring of or direct consumption of a chilled beverage from a can, it is normal to employ a perforating tool by means of which the top of a beverage can can be punctured to permit the escape of the beverage therefrom. The cans which are likewise chilled make it desirable that they be provided with a handle in order that the fingers do not come in contact with the walls of the can. Accordingly, it is the object of this invention to provide a combination opener or punch and handle which may be utilized to first punch the top of the can and, which in its punching operation, is so firmly secured to the can that it may be used as a handle.

It is another object of this invention to provide such a combination can punch and handle which may be manufactured very cheaply from a single strip of metal.

It is another object of this invention to provide a combination can punch and handle which does not extend below the bottom of the can in order that the latter is entirely stable when placed upon a flat surface, such as a table.

In the drawings which illustrate the invention,

FIGURE 1 is a perspective view of the device embodying the invention.

FIGURE 2 is a side view of the can punch and handle in its operative position,

FIGURE 3 is a front view of the punch and handle, showing the method of operation thereof,

FIGURE 4 is a perspective front view of an alternative embodiment of the punch, and

FIGURE 5 is an enlarged sectional view taken on the line 5—5 of FIGURE 4, illustrating yet another embodiment of the punch.

Referring to the drawings the type of can, herein accorded the numeral 10, with which the punch and opener is to be employed, is of a familiar type having a side wall 12 and a head 14 united at their juncture by an outwardly extending bead 16.

The punch and handle device is formed of an elongated one piece strap 17 composed of a rigid material, such as steel, and bent into a U shape at substantially its middle length to form a pair of parallel legs 19 and 20. A triangularly shaped elongated pointed tongue 23 is stamped out of leg 19 said tongue having a flat elongated undersurface 24 extending in the plane of the leg 19 from the base 26 of the tongue almost to the tip 27 of the latter, the tip being bent slightly outwardly out of the plane of the undersurface 24.

Extending adjacent the base 26 of the tongue the leg 19 is formed having a short sharp arcuate bend as at 30 to space the lower portion 31 of said leg inwardly of the undersurface 24 of said tongue, but parallel thereto, the space between said lower portion 31 and said undersurface 24 being sufficient to accommodate the width of the bead 16 of the can. The side edges of the lower portion 31 of the leg 19 are turned outwardly to form a pair of longitudinally extending ribs 32 and 33 spaced apart from each other and spaced from their adjacent sides of the tongue, the upper ends 34 and 35 respectively of said ribs being spaced to form abutment surfaces and terminating at the bend 30, and their outer longitudinal edges 37 and 38 respectively lying in the plane of the

2

undersurface 24 of said tongue. Upper end 34, at its juncture with its abutment surface, forms a sharp corner 34a while the corner 35a formed at the juncture of upper end 35 and its abutment surface is rounded.

5 In order to use the apparatus to punch a can, the punch ends of one of the side ribs, for instance corner 34a, is positioned beneath the bead 16 on the outer surface of the side wall 12 and with the tip 27 of the tongue resting against the head 14 of the can. In this position, it will be seen that the leg 20 which, it is intended shall serve as the handle, extends at an angle to the longitudinal axis of the can. This position of the opener to the can is shown in FIGURE 3 of the drawings.

The leg 20 is then rotated in the direction as shown 15 by the arrow downwardly to an upright position. The sharp corner 34a of rib 32 during the rotatable movement of the leg 20, serves as a fulcrum about which said leg is rotated, thereby swinging the tongue downwardly into the can adjacent the inner surface of the side wall 20 thereof and puncturing the head. At the same time, the rib 33 is swung downwardly over the outside of the bead and the outer surface of the side wall 12 until its upper end 35 also rests below the bead 16.

In this position it will be seen that with the ribs 32 25 and 33 pressing against the outer surface of the side wall 12, and with the tongue pressing against the inner surface thereof, the opener will sufficiently grip said side wall that the handle may not be rotated outwardly away therefrom. It will also be observed that the can may not 30 slip downwardly out of the grip of the rib and the tongue as the upper edges 34 and 35 of said ribs will engage the bead 16. The release of the opener is facilitated, when it is rotated in the opposite direction, by the rounded corner 35a.

35 FIGURE 4 illustrates another embodiment 50 of the punch. In embodiment 50, the tongue 52 thereof which corresponds to tongue 23, is arcuately shaped as a scimitar, having one edge 53 thereof sharpened so that it may easily slice the head 14 of the can to which it may be applied.

FIGURE 5 illustrates another embodiment 60 of the punch. In embodiment 60, the tongue 62 which may be shaped in the form of tongue 52 or tongue 23, is provided with a raised rib 64 on its undersurface and extending 45 from the base of said tongue to its tip. This rib tightly engages the inner surface of the side wall of the can when the punch is used to open the can, the operation being hereinbefore described, and slightly deforms said side wall. The normal resiliency of the material 50 therefore enhances the grip of the punch on the side wall and reduces any tendency that the punch may have for tipping inwardly when it is used as a handle.

What I claim as my invention is:

55 1. A combined can punch and handle comprising a U-shaped strip of material forming a pair of spaced parallel legs and having an elongated pointed tongue depending from the base of one leg, said tongue being adapted to pierce the head of a can and to extend downwardly adjacent the interior surface of the side wall of the can, a pair of parallel elongated rib elements formed on said one leg extending parallel to and spaced apart on either side of the tongue and being adapted, when the tongue is inserted into the can, to press against the outer surface of the can's side wall, and abutment surfaces at the upper ends of the rib elements arranged to bear against the underside of the top bead of the can so as to grip the latter, thereby permitting the other leg 60 of the U-shaped strip to serve as a handle.

65 2. A combined can punch and handle as claimed in claim 1 including a raised rib extending longitudinally

of the tongue adapted, when the tongue is positioned so as to extend into the can, to press upon the interior surface of the side wall of the latter.

3. A combined can punch and handle comprising a U-shaped strip of rigid material forming a pair of spaced parallel legs and having an elongated pointed tongue depending from the base of one leg, said tongue being shaped and positioned to pierce the head of a can and to extend downwardly adjacent the interior surface of the side wall of the can and having one side edge formed as a cutting edge, a pair of parallel elongated rib elements formed on said one leg extending parallel to and spaced apart on either side of the tongue and being adapted, when the tongue is inserted into the can, to press against the outer surface of the side wall of the can, and abutment surfaces at the upper ends of the rib elements arranged to bear against the underside of the top bead of

the can so as to grip the latter, thereby permitting the other leg of the U-shaped strip to serve as a handle.

4. A combined can punch and handle as claimed in claim 3 in which said one side edge is arcuately shaped.
